PAINT SPRAYING APPLIANCE

Application filed May 31, 1930. Serial No. 458,836.

Our invention relates to the class of spray appliances in which a stream of compressed air is projected past the outlet of a liquid supply tube leading from a container on which the air-projecting part of the appliance is mounted, so that the air stream sucks liquid material out of the liquid supply tube and atomizes this liquid.

Generally speaking, the objects of our invention are the providing of an exceedingly light, inexpensive and easily manufactured spray appliance of this class, and one in which no air valve or other accurately machined mechanism is required for controlling the spray.

More particularly, our invention aims to provide a spray appliance of this class, in which the volume and distribution of the spray can be regulated by adjusting a liquid outlet nozzle, and in which the spraying action is controlled (without interrupting the flow of air through the air duct) by means of an air deflector which is movable into and out of a position between the air outlet and the liquid outlet. Moreover, our invention aims to provide simple, inexpensive and easily operated mechanism whereby the user of the appliance can easily and conveniently control the spraying action.

Still further and also more detailed objects will appear from the following specification and from the accompanying drawing, in which

Fig. 1 is a side elevation of a spray appliance embodying our invention, with a portion of the liquid container broken away, showing the parts as they are disposed when the spraying is discontinued.

Fig. 2 is a fragmentary view, similar to a portion of Fig. 1 but with some parts in section, showing the positions of the air deflector and the deflector-moving mechanism as they appear during the spraying action.

Fig. 3 is a fragmentary plan view of the cap of the liquid container and of parts disposed above this cap.

Fig. 4 is a fragmentary side elevation, partly in section, showing a simplified form of air deflector and deflector-moving mechanism also embodying our invention.

In the embodiment of Fig. 1, the material container consists of a jar 1 and a cap 2 threaded upon the mouth of the jar. Seated on the top of the cap 2, and clamped to the cap by a screw 3, is the foot 4 of a leg 5 which depends from the barrel or air tube 6 of pistol-shaped spray gun body. This body (which desirably is a casting made of a light metal, such as aluminum) also includes a handle 7 depending from a more rearward portion of the barrel or air tube 6, and the barrel has an inlet portion or attaching nipple 6A, projecting rearwardly beyond the upper end of the handle, which projection desirably is corrugated (as shown in Fig. 1) to facilitate the tight attaching of the hose 8 through which compressed air is supplied to the air tube. Thus arranged, the foot 4 and the leg 5 form the base member for supporting the entire spray gun body (including the air tube, the attaching nipple and the handle), which body can be an integral casting—
as for example, of aluminum or an aluminum alloy.

The air tube preferably extends forwardly beyond the leg 5 and has its forward end 75 tapering forwardly, and the outlet portion O of the air tube (which outlet portion opens through this forward end of the tube) is considerably smaller than the main portion B of the bore of the air tube, so as to accelerate the 80 velocity of the issuing stream of air.

Extending slidably downwardly through the foot 4 of the gun body and the cap 2 is a liquid supply tube 9 which depends into the liquid in that jar. This liquid tube also extends through a packing disk 10 which is clamped against the lower face of the cap top by a screw 3 and which effectively seals the tube to the cap in addition to affording the usual seal between the cap and the mouth end 90 of the jar.

Threaded upon the upper end of the liquid tube 9 is a liquid nozzle 11, which has an upwardly tapering bore and which presents its tip end somewhat below the axis A of discharge bore O of the air tube. Interposed between the bottom of the liquid nozzle 11 and the foot 4 is a compression spring 12 which serves the double purpose of latching the nozzle 100

zle against rotation on the tube, and of lifting the nozzle and the liquid tube to a position in which the bottom of the packing 10 is engaged by a stop collar 13 soldered to the tube.

Extending horizontally through the air tube, behind the tapering tip of this tube and above the tube axis A, is a pivot pin 14, which pin has its axis in a plane at right angles to the common vertical plane of the air tube axis 10 A and the liquid nozzle axis N. Pivoted upon this pin 14 is an air deflector member, here shown as comprising a concaved air deflector 15 concentric with the pivot pin 14, and two sides 16 extending upwardly and rearwardly 15 at opposite sides of the forward portion of the air duct, these sides being journaled on the pivot pin 14.

This air deflector member is so proportioned that its curved air deflector portion 15 can swing freely between the liquid nozzle 11 and the outlet tip of the air duct, thereby permitting the air deflector to be moved into and out of positions in which it will intercept and deflect the air issuing from the air tube, so 25 that this air cannot pass close to the upper or discharge end of the liquid nozzle.

For moving the air deflector, Figs. 1 and 2 show a bar 16 extending slidably below the air tube through the leg 5 and into a bore 17 in the 30 upper portion of the handle. The forward end of this sliding bar 16 has a horizontal pin 18 extending through the bar, and each end portion of this pin is disposed in a slot 19 formed in the lower end of one of the sides 16 35 of the deflector member, each such slot being elongated radially of the axis of the pivot pin 14. A compression spring 20 disposed between the rear end of the sliding bar 16 and the rear end of the bore 17 continually urges 40 this bar forwardly until stopped by the engagement of the rear face of the leg 5 with the forward end of a finger-piece 21 which is fastened to the sliding bar by a cross-pin 22. This finger-piece depends below the air tube and between the liquid container and the handle 7, so as to be easily reached and 45 manipulated by a finger of a hand grasping the handle.

When the sliding bar is not digitally retracted, the spring 20 retains it in the position 50 shown in Fig. 1, thus holding the air deflector member in a position in which the air deflector 15 extends in front of the air outlet O. Consequently, compressed air supplied by the 55 hose 8 and passing through the air tube will be deflected upwardly and at such a distance from the tip of the liquid nozzle 11 as to exert no suction effect for drawing liquid up the liquid tube.

60 However, when the sliding bar is retracted, as shown in Fig. 2, the air deflector is swung entirely below the outlet of the air tube, so that the issuing air blows across the tip of the liquid nozzle, thereby sucking liquid out 65 of the jar 1 through the liquid tube 9 and the

said nozzle, so that this liquid issues from the tip of the nozzle and is atomized into a spray by the stream of air issuing from the air tube.

With the parts in this disposition, the total volume, density and spread of the spray can be varied to a considerable extent by merely rotating the liquid nozzle 11, so as to vary the distance between its tip and the axis A of the air tube. Whenever the spraying is to be interrupted or discontinued, the operator 70 merely releases his rearward pressure on the fingerpiece; whereupon the spring 20 slides the bar 16 forward and returns the air deflector to the position shown in Fig. 1, in which this deflector diverts the air upwardly and 75 out of operative effect on the liquid nozzle and the liquid tube.

To allow the liquid to be sucked out of the jar, the cap 2 is provided with a suitable air vent, such as the perforation 23 in Fig. 3, thereby allowing the pressure of the outer air to press down on the liquid in the jar so as to force the liquid up the tube 9 and out of the liquid nozzle 11.

When the spring is pushing the slide bar 16 forwardly, the air deflector 15 swings (in a clockwise direction in Figs. 1 and 2) so that its upper edge moves upwardly in front of the tip of the air duct, thereby swinging the air blast upwardly. As the result of this upward tilting or swinging movement of the air blast, the lower edge of the issuing air stream still strikes the tip of the liquid nozzle after the major portion of the air has been deflected sufficiently to annul its sucking action, thereby blowing off any petty drop of liquid which otherwise might be held in the tip of the liquid nozzle by capillary action. Consequently, we avoid the clogging of this nozzle by having paint or the like dry in its tip.

By using a straight bore for the air tube and eliminating the need of an air valve, we also obviate a clogging of the air outlet by dust in the air, in addition to avoiding the need of accurately machined valve parts. And, since the extending of the liquid tube through the cap of the container prevents the body of the spray gun from rotating about the screw 3, this single screw suffices for securing the spray gun to the container. Moreover, the liquid tube can readily be separated from the cap when the nozzle 11 is unscrewed, so that the user easily has access to all parts for inspecting and cleaning them.

However, while we have heretofore described our invention in an embodiment including a sliding member for moving the air deflector in one direction, we do not wish to be limited to this or other details of the construction and arrangement thus described, since many changes might be made without departing either from the spirit of my invention or from the appended claims.

For example, Fig. 4 shows a portion of an

embodiment of our invention in which the air deflector is integral with the actuating member, and in which no sliding member is required. In this embodiment, the actuating member is a lever 24 pivoted intermediate of its length on a horizontal pin 25 extending through a riser lug 26 formed on the air tube 6 at a short distance from the tapering tip of this tube, and this lever (which can be punched out of sheet metal) has its forward end bent downward to form an air deflector 27. A compression spring 28 is interposed between the air tube 6 and the lever 24 rearwardly of the pivot pin 25 and continuously tends to swing the forward lever arm downwardly, so as to have the air deflector 27 extend across the axis A of the air tube. But the swinging of the lever in this direction is limited by a screw 28 which is threaded through the forward lever arm and has its lower end disposed for engaging the top of the air tube. With this embodiment, a downward pressure on the rear lever arm (as by the finger 29) will rock the lever so as to raise the air deflector out of the path of the air projected from the air tube, and the spring will automatically return the combined air deflector and actuating member to the screw-stopped position when the pressure of the finger is discontinued.

With each of the illustrated embodiments, the axes of the liquid nozzle and of the discharge passage O of the air tube should be in a common vertical plane, such as the plane P in Fig. 3, to insure symmetry in the resulting spray. However, no great accuracy of manufacture is otherwise required for either embodiment. Moreover, it will be obvious that an exceedingly small amount of machining is required for our entirely valveless spray appliance, that the assembling is quite simple; and that the entire spray gun portion can be much lighter than that of types which include interior valves and valve-actuating mechanisms.

We claim as our invention:

1. In a spraying appliance, a container for liquid, a body member including a base seated on the container, a riser on the base, an air tube extending across the top of the riser, and a handle depending from the rear end of the air tube, the air tube having its outlet above the said base; a liquid tube extending upwardly through the top of the container and the base, and having its outlet disposed forwardly of the outlet of the air tube, the axes of both outlets being in a common vertical plane and the upper end of the outlet of the liquid tube being below the axis of the air tube; an air deflector pivoted to a forward portion of the air tube on a horizontal axis transverse of the axis of the air tube, the air deflector having a portion thereof adapted to extend across the mouth of the air tube when the air deflector is in one posi-

tion; a slide extending through the riser below the air tube and connected to the air deflector; spring means interposed between the slide and a portion of the body member for continually urging the slide in a direction in which the slide causes the deflector to be in the aforesaid position; and means operable by a hand grasping the handle, for moving the slide in the opposite direction against the resistance of the spring.

2. In a spraying appliance, a container for liquid, a body member including a base seated on the container, a riser on the base, an air tube extending approximately horizontally across the top of the riser, and a handle depending from the rear end of the air tube, the air tube having its outlet above the said base; a liquid tube extending upwardly through the top of the container and the base, and having its outlet disposed forwardly of the outlet of the air tube, the axes of both outlets being in a common vertical plane and the upper end of the liquid tube outlet being below the axis of the air tube; an air deflector pivoted to a forward portion of the air tube on a horizontal axis transverse of the axis of the air tube, the deflector having a portion thereof adapted to extend across the mouth of the air tube when the said deflector is in one position; a slide extending through the riser below the air tube and connected to the air deflector; spring means interposed between the slide and a portion of the body member for continually urging the slide in a direction in which the slide causes the deflector to be in the aforesaid position; and a combined stop and trigger element fast upon the slide behind the riser and forwardly of the handle, the said element including a depending trigger and shouldered portion forwardly of the trigger and disposed for engaging the riser when the slide is sufficiently moved by the spring in the first named direction to dispose the air deflector in its said position.

3. In a spraying appliance, a container for liquid, a riser tube depending into and extending above the container and having a contracted liquid outlet at its upper end; an air tube extending transversely of the said riser tube above the container and having a contracted air outlet disposed adjacent to the said liquid outlet, with the axis of the air outlet above the liquid outlet; an imperforate air deflector pivoted upon the air tube and movable into and out of a position in which the said deflector extends between the said two outlets, the air deflector being formed for upwardly deflecting air issuing from the said air outlet.

4. A spraying appliance as per claim 3 in which the air deflector also has side wings for laterally confining the air which issues from the air outlet when the deflector is disposed between the two outlets.

5. In a spraying appliance, a container for liquid, a riser tube depending into and extending above the container and having a contracted liquid outlet at its upper end; an air tube extending transversely of the said tube above the container and having a contracted air outlet disposed adjacent to the said outlet and with the axis of the air outlet above the liquid outlet; an air deflector pivoted to the air tube and movable into and out of a position in which a portion of the air deflector is disposed between the two outlets, a retracting member slidably supported below the air tube and connected to the air deflector for moving the air deflector in one direction, and spring means opposing such movement of the retracting member.

6. In a spraying appliance, a base member, a liquid tube and an air tube supported by the base member with the axes of the two tubes relatively transverse, and with the outlets of the two ducts so disposed that air issuing from the air tube will blow across the outlet of the liquid duct to produce suction in the liquid tube towards the outlet of that tube; and an upwardly open scoop-shaped air deflector having its sides extending at opposite sides of the air tube and having the upper ends of its sides conjointly pivoted to the air tube, the deflector being movable into and out of a position in which its back extends across the axis of the air tube.

7. In a spraying appliance, a container for liquid, a body member including a base seated on the container, a riser on the base, an air tube extending approximately horizontally across the top of the riser, and a handle depending from the rear end of the air tube, the air tube having its outlet above the said base; a liquid tube extending upwardly through the top of the container and the base, and having its outlet disposed forwardly of the outlet of the air tube, the axes of both outlets being in a common vertical plane and the upper end of the liquid duct outlet being slightly below the axis of the air tube; an air deflector pivoted to a forward portion of the air tube on a horizontal axis transverse of the axis of the air tube, the deflector having a portion thereof adapted to extend across the axis of the air tube when the said deflector is in one position; and an actuating member extending slidably through the riser and into the handle and connected to the air deflector.

8. A spraying appliance as per claim 7, in combination with spring means interposed between the actuating member and the handle for continuously urging the actuating member in the direction in which the latter causes the deflector to extend across the axis of the air tube.

9. A spraying appliance as per claim 7, in combination with spring means interposed between the actuating member and the handle for continuously urging the actuating

member in the direction in which the latter causes the deflector to extend across the axis of the air tube, and a trigger member disposed between the said riser and handle and fastened to the actuating member, the trigger member having its ends respectively disposed for engaging the riser and the handle so as to limit the movement of the actuating member in both directions.

Signed at Chicago, Illinois, May 26, 1930. 75.
